UNITED STATES PATENT OFFICE.

RUDOLPH A. SCHWAHN, OF EAU CLAIRE, WISCONSIN.

DESIGN FOR A SHIELD-BUCKLE.

44,941.

Specification for Design.

Patented Nov. 25, 1913.

Application filed September 19, 1913. Serial No. 790,799. Term of patent 14 years.

To all whom it may concern:

Be it known that I, RUDOLPH A. SCHWAHN, a citizen of the United States, residing at Eau Claire, in the county of Eau Claire and State of Wisconsin, have invented a new, original, and ornamental Design for Shield-Buckles, of which the following is a specification, reference being had to the accompanying drawing, forming part thereof.

Figure 1 is a front elevation of the shield

buckle, showing my new design. Fig. 2 is a rear elevation of the same. Fig. 3 is a side edge elevation of the buckle.

I claim:

The ornamental design for a shield buckle, as shown.

RUDOLPH A. SCHWAHN.

Witnesses:

LOUIS W. SCHWAHN,
N. S. WOODRUFF.
